UNITED STATES PATENT OFFICE.

HALL H. HOLDWAY, OF LONG BEACH, CALIFORNIA.

ROTARY PIPE TONGS.

Application filed April 7, 1926. Serial No. 100,238.

My invention relates to pipe tongs such as are used on oil well casing and such as are suspended in the derrick and are swung into engagement with a casing which is to be turned and which must be adjusted to and locked in order to turn said casing.

Among the salient objects of my invention are: to provide a device of the character referred to which can be moved into engagement with a well casing and in which the jaws thereof are automatically closed around the casing and locked for operation without the necessity of the operator going over to the casing or in any other manner manipulating the head of the wrench or tongs; to provide such a device constructed and arranged to be moved longitudinally or in an endwise manner into engagement with the well casing, the gripping jaws thereof opening outwardly so that as the device is thus moved endwise against the casing, said jaws close around the casing and lock for operating; to provide in such a device means extended back along the handle for releasing the jaws for removing said tongs from the casing, thus making it unnecessary for the operator to go to the casing in order to apply or release the tongs; and, in general, to provide a simple, practical and efficient device of the character referred to.

In order to fully explain my invention, I have illustrated the same on the accompanying sheet of drawings, which I will now describe.

Figure 1 is a perspective view of tongs embodying my invention, with the top plate removed to show the interior arrangement thereof;

Figure 2 is a similar view of the device as applied to a piece of well casing;

Figure 3 is a view of the top plate removed from the device as shown in Figs. 1 and 2;

Figure 4 is a top plan view of the body or head of the device; and

Figure 5 is a detail view showing a slightly modified handle and jaw connection.

Referring now in detail to the drawings, my invention as here embodied, comprises a body having a somewhat crescent form with the fixed plate, 6, the integrally formed edge member, 7, of irregular form, substantially as illustrated, the handle, 8, the removable top plate, 9, the two pivoted jaws, 10 and 11, a pivoted connecting link, 12, pivoted on the bolt, 13, and at one end pivotally connected to the inner end of the handle, 8, as at 14, and

at its other pivotally connected to the jaw, 10, and the fixed jaw member, 15, provided with gripping teeth, 16, as is also pivoted jaw, 11, which teeth are shown to be removable from the faces of the members 15 and 11.

Pivotedly mounted between the top and bottom plates, 6 and 9, between the fixed jaw member, 15, and the integral edge portion, 7, is a pivoted dog or pawl, 17, on the bolt, 18, with its free end adapted to engage in a notch or recess, 19, in the pivoted jaw, 11, as is clear from Figs. 1 and 2. An operating rod, 20, is connected with said dog, 17, and extended along the handle, 8, for convenient operation to remove the dog, 17, from said notch or recess, 19, to release said pivoted jaw, 11. A spring, 21, set in the inner face of the integral member, 7, normally moves said dog or pawl, 17, inwardly into engagement with said pivoted jaw, 11, as is clearly illustrated.

The pivoted jaws, 10 and 11, are each provided with slots, as 10', and 11', within which are placed springs, as 22, to normally move said jaws to the open positions, represented in Fig. 1. This is a simple arrangement and need not be further illustrated or described.

In Figs. 1 and 2, the handle, 8, is shown pivotally mounted on a bolt, 23, through the body of the device, and pivotally connected with the link, 12, as at 14, so that movement of said handle to the right, operates to move said link, 12, on its pivot, 13, and to move the jaw, 10, inwardly, or outwardly, depending on the movement of said handle to the right, or to the left, as shown in Figs. 1 and 2, and as will be understood from the showing.

In Fig. 5, I have shown a slightly modified handle, 8^a, with the link eliminated, said handle having the integral portion, 12^a, pivotally connected at its end with the pivoted jaw, 10^a, corresponding with the jaw, 10. In this arrangement the pivot bolt, 23, can be omitted, and the pivotal connection or mounting of said handle 8^a, made on the bolt, 13, for the movement of the jaw, 10^a, to and from the casing, designated, C, Fig. 2.

These tongs are heavy and are usually suspended in the derrick, and to this end they are provided with the eyes, as 23', on the handle, and 24, 24, on the opposite edges of the plate, 9, as illustrated. Of course any suitable means can be provided for suspending the tool in a swinging condition for use.

The use and operation of the invention may be briefly described as follows:

Assuming that it is suspended in a derrick

with its jaws, 10 and 11, open, as illustrated in Fig. 1, it is only necessary for the operator to swing it endwise to and into engagement with the well casing to be turned. As the tool and its jaws, 10 and 11, in particular, engage the casing, C, said jaws will be forced to close around the casing, C, in the manner illustrated in Fig. 2. This is accomplished by simply thrusting the tongs onto the casing. The dog, or pawl, 17, engages in the recess, 19, and the jaw, 11, is held locked against the casing, which also locks the jaw, 10, for it cannot be opened without releasing the jaw, 11, by pulling on the rod, 20, to remove the pawl or dog, 17. It is not necessary for the operator to leave the end of the handle to adjust the tool on the casing, or to fasten the jaws, for they automatically lock thereupon.

As said handle is operated now, say to the right; as shown in Figs. 1 and 2, it operates through the link, 12, to force the jaw, 10, more tightly against the casing, which forces the casing more tightly against the jaw, 11, and the continued movement of the handle to the right, turns said casing. When it is desired to release the tool from the casing, it is only necessary to pull the rod, 20, which releases the dog, 17, and then pull the tool lengthwise from the casing. The whole operation of applying, using and removing the tool can be accomplished from the handle end thereof and without going to the casing at all. If the handle, as arranged in Fig. 5, is used, it is moved in the opposite direction to tighten or loosen the jaw, 10^a, as will be understood, and the releasing rod, 20^a, is operated in the same manner as is the rod, 20, to release the dog.

I am aware that changes in the details of construction and arrangement can be made without departing from the spirit of my invention, and I do not, therefore, limit the invention to the showing made, except as I may be limited by the hereto appended claims.

I claim:

1. Pipe tongs including in combination, a handle, side plates of substantially crescent form attached to said handle with their openings in vertical register when said tongs are used on vertical pipe, said openings being at the outermost end of said handle, whereby when said handle is moved longitudinally to a pipe said openings pass over said pipe, pivoted jaw members in the opposite sides of said openings with semi-circular gripping faces opposite each other and opening outwardly and adapted to first engage a pipe as said tongs are moved endwise against a pipe, said pivoted jaws being adapted to move simultaneously together into said crescent shaped side plates and around opposite sides

of said pipe as said tongs are thrust endwise against said pipe, latch means rearwardly of said jaws for holding them closed as they are moved back into said crescent shaped side plates, and operating connections from said handle with one of said jaws to press the same against said pipe as said handle is moved laterally in one direction.

2. Pipe tongs including in combination, a handle, opposed side plates at the outer end of said handle, said side plates having U-shaped openings in their outer ends in alignment with said handle and opening outwardly, whereby to move over a pipe when said handle is thrust longitudinally toward said pipe, gripping jaws pivotally connected to the opposite sides of said U-shaped plates to swing inwardly toward each other into the opening of said plates to embrace a pipe when moved thereagainst by the endwise movement of said handle, latch means for holding one of said jaws closed and operating thereon rearwardly of said pipe, the outermost parts of said jaws being free of any fastening means, and operating connections from said handle to one of said jaws in said side plates for moving said jaw against said pipe when said handle is moved laterally in one direction, whereby said tongs can be moved endwise against a pipe and moved laterally to automatically grip said pipe for turning the same.

3. In pipe tongs, in combination a body having a U-shaped opening therein to receive a pipe therein, a handle pivotally connected thereto at the bottom of said U-shaped opening and extending longitudinally thereof in Y-form, two pivoted pipe engaging jaws in the mouth of said U-shaped opening and swinging outwardly away from each other to open and form the outermost mouth portions of said tongs and swinging inwardly toward each other into said U-shaped opening as said tongs are moved longitudinally of said handle and endwise against a pipe, said jaws closing simultaneously about the opposite sides of said pipe by said endwise thrust against the same, latch means rearwardly of said pipe in said body for holding said jaws inwardly, and operating connections from said handle, within said body, with one of said jaws and adapted to move it against said pipe in biting engagement therewith as said handle is moved laterally in one direction, whereby said tongs can be moved lengthwise in an endwise thrust against a pipe to attach it and moved laterally in one direction to automatically grip said pipe in operating engagement.

Signed at Los Angeles, Los Angeles County, California, this 31st day of March, 1926.
HALL H. HOLDAWAY.
